UNITED STATES PATENT OFFICE

THOMAS G. COGHLAN, OF ELIZABETH, NEW JERSEY

ASH DISPOSAL SYSTEM

Application filed April 22, 1929. Serial No. 356,941.

The invention relates to disposal systems for ash or slag from boiler furnaces or smelting furnaces; and it has for its object a novel combination of apparatus whereby this may be expeditiously and economically effected through the use solely of water as an advancing medium. A further object of the invention is to greatly increase the percentage of material that may be handled 10 with a given volume of water.

Heretofore, it has been proposed to utilize pumps, or devices having more or less obstructed passageways, in removing the water-slued ash or like material; but this 15 type of apparatus is short-lived and does not afford a satisfactory solution of the problem of ash disposal, more especially in connection with the operation of large power plants and smelting furnaces. In accordance with the present invention, no moving parts are utilized for this purpose; and in carrying out the same, the ash or slag to be removed is, preferably, first prepared in a 20 condition for ready sluicing by water and is fed thereby to the suction side of the removal device. This device is provided with a straight-away through passageway and is operated also by water which is combined 25 with the water-slued material and the mixture propelled into a closed disposal line for final discharge, the water eventually being separated from the ash, for example, when the same is delivered to a storage hopper or the like from which the ash may be 30 further distributed, as by being conveyed therefrom in suitable cars.

The nature of the invention, however, will best be understood when described in 35 connection with the accompanying drawings, in which:

Fig. 1 illustrates in elevation and part section the novel disposal system as applied to a boiler furnace of the non-slagging type.

Fig. 2 is a similar view of the application of the novel disposal system to a slagging type furnace.

Fig. 3 is a longitudinal section through 50 the removal member which affords, also, additional volumes of the sluicing medium.

Fig. 4 is a part transverse section and end elevation thereof.

Referring to the drawings, more particularly Fig. 1, 10 designates one of a pair of grinder rolls, located at the bottom of an 55 ash-receiving hopper 11, and such as are preferably installed in connection with non-slagging boiler furnaces from the grate of which ash is discharged, the purpose of said rolls being to sufficiently crush or disintegrate the solid material so that it may readily flow along a sluiceway or launder 12 located beneath said grinder apparatus. Water, which is introduced through the pipe 13 into the sluiceway 12, is utilized as the 60 medium for advancing or accelerating the disintegrated ash along the same until it is caught up at the suction side of the removal member 14 which provides sufficient head to force the sluiced material to the point of 65 final distribution. This, for example, may consist of a bin or hopper 15 to which the discharge conduit 16, constituting a closed disposal line from the removal member 14, 70 discharges the mixture of water and disintegrated ash. An overflow pipe 17 is provided in connection with the bin 15 for removal of the surplus water; and the bin may be elevated sufficiently to discharge into suitable cars 18 passing thereunder and serving 75 to convey the solid material therefrom.

The removal member itself is more particularly shown in Figs. 3 and 4; and comprises a casing having an inlet chamber or 80 suction portion 20 into which the liquid vehicle and disintegrated material is received, and an outlet or frusto-conical portion 21 from which it is discharged under pressure, the said device being included in the system, 85 as indicated in Fig. 1, between the sluiceway 12 and the disposal line 16.

In order to provide the additional supply of liquid vehicle for enhancing the flow and to afford sufficient suction for drawing the initial mixture through the device and discharging the same under pressure to accelerate and propel it into said conduit 16, the inlet or suction portion 20 is surrounded by an annular chamber 22 to which water is supplied through an inlet pipe 23 connected 90 to

therewith and under sufficient head. In addition, a series of discharge openings 24 are arranged circularly at the outlet end of the chamber 22 and are designed to receive nozzle members 25 screwed therein, as indicated. The latter are directed at an angle to the common longitudinal axis of the coaxial inlet and outlet portions 20 and 21 so that the various streams or jets issuing therefrom will converge to a common point substantially in the said axis and will form a conical shell of water issuing from the annular chamber 22. This serves to set up an effective suction or vacuum in the chamber portion 20 to advance the mixture of water and contained material through said portions 20 and 21 and also to establish sufficient pressure to force the same outwardly from the chamber 21 against a reasonable head such as may prevail in the disposal line 16, although it is to be understood that in some instances the material may merely be advanced against a slight head and projected over a considerable distance for various purposes, such as filling, etc. It is to be noted, furthermore, that the angle at which these jets are discharged must be in such relation to the common longitudinal axis of the chambers 20 and 21 as to provide for the convergence of these jets at a point sufficiently far removed from the former chamber as to prevent any backing-up of the material. I have found that an angle of approximately $22\frac{1}{2}$ ° affords a suitable jet for the purpose.

By the foregoing expedient, not only is appreciable suction provided for advancing the sluicing vehicle and disintegrated material and for forcing the same against a substantial head, but the medium employed for effecting this suction, to wit: water, further serves to enhance the flow effect; and greatly increased proportions of the solids may be handled than heretofore, amounting generally approximately to thirty per cent.

It has been found desirable, also, to provide means to protect the nozzles 25 against the action of the rapidly-moving ash particles; and to this end, the outer portion of the inlet chamber may be counterbored to form a seat 26 into which is fitted a hollow cylindrical guard piece 27 extending the chamber somewhat beyond its natural end and substantially to the mouth of the said nozzles. As this guard becomes worn, it can readily be replaced; and it effectively protects the nozzles which, of course, are more difficult and more expensive to replace. A cleanout valve 28 may, also, be connected with the annular chamber 22.

As indicated in Fig. 2, the novel system is applicable also to the removal of other types of ash, for example, slag from a slagging type of boiler furnace, or a smelting furnace, as the furnace 30 from which slag

is drawn through the spout 31. In this embodiment, the slag is received through a funnel opening 32 which delivers the same into a sluicing chamber 33 through which water is designed to be discharged axially by means of a pipe or nozzle 34. The liquid slag, of course, cannot be disintegrated mechanically as in the case of solid ash, but the action of the water stream thereon effects a spontaneous disintegration of the material so that it is readily advanced and propelled by the removal member 35 which is similar to the device 14 of the previously described embodiment and is connected with the sluicing chamber 33 in this instance.

I claim:

1. In an ash disposal system provided with a sluiceway and a closed disposal line: means for introducing water to the sluiceway for advancing the ash therethrough, a removal member comprising a casing having an unobstructed inlet chamber in communication with the sluiceway and a coaxial unobstructed discharge chamber for the mixture of ash and water and communicating directly with the inlet chamber, an annular chamber surrounding the inlet chamber and having an inlet for water thereto, circularly disposed discharge nozzles at the outer end of the annular chamber and through which water is projected at an angle to converge the streams to a point substantially beyond the outlet of the inlet chamber to provide suction in the inlet chamber and accelerate and propel the said mixture through the discharge chamber into the disposal line, and a hollow cylindrical member set into the inlet chamber to extend beyond the same for protecting the nozzles against ash issuing from said chamber under the suction developed by the nozzles.

2. In an ash disposal system provided with a sluiceway and a closed disposal line: means for introducing water to the sluiceway for advancing the ash therethrough, a removal member comprising a casing having an unobstructed inlet chamber in communication with the sluiceway and a coaxial unobstructed discharge chamber for the mixture of ash and water and communicating directly with the inlet chamber, an annular chamber surrounding the inlet chamber and having an inlet for water thereto, circularly disposed discharge nozzles at the outer end of the annular chamber and through which water is projected at an angle to converge the streams to a point substantially beyond the outlet of the inlet chamber to provide suction in the inlet chamber and accelerate and propel the said mixture through the discharge chamber into the disposal line, and a sleeve fitting within and shouldering against a counter-bored section of the inlet chamber to extend said chamber substantially to the ends of the nozzles for protecting

them against ash issuing from the said inlet chamber under the suction developed by the said nozzles.

3. In a disposal system: a removal member comprising a casing having a substantially unobstructed through passageway and the inlet portion thereof affording a suction chamber to receive the matter to be disposed of, a single ring of individual nozzles about the passageway at the far end of the suction chamber and terminating substantially at said far end to maintain substantially the bore of the passageway, said nozzles being inclined at an angle of approximately 22½° to the longitudinal axis of the passageway to direct individual separated streams of water therein converging substantially at a point in said axis removed from the outlet of the suction chamber, and 20 a manifold about the suction chamber to supply water to all of the said nozzles at substantially the same pressure.

4. In a disposal system: a removal member comprising a casing having a substantially unobstructed through passageway and the inlet portion thereof affording a suction chamber to receive the matter to be disposed of, a single ring of individual nozzles about the passageway at the far end of the 25 suction chamber and converging toward the discharge end, said nozzles terminating substantially at said far end to maintain substantially the bore of the passageway and being inclined at an angle of approximately 22½° to the longitudinal axis of the passageway to direct individual separated streams of water therein converging substantially at a point in said axis removed from the outlet of the suction chamber, and 40 a manifold about the suction chamber to supply water to all of the said nozzles at substantially the same pressure.

In testimony whereof I affix my signature.
THOMAS G. COGHLAN.
